UNITED STATES PATENT OFFICE.

ANDREW B. MILLER, OF BALDWIN, WISCONSIN, ASSIGNOR OF ONE-THIRD TO EDWARD CHRISTENSON, OF BALDWIN, WISCONSIN.

FRUIT-JAR-COVER REMOVER.

1,396,867.

Specification of Letters Patent.

Patented Nov. 15, 1921.

Application filed July 2, 1920. Serial No. 393,495.

To all whom it may concern:

Be it known that I, ANDREW B. MILLER, a citizen of the United States, residing at Baldwin, in the county of St. Croix and State of Wisconsin, have invented certain new and useful Improvements in Fruit-Jar-Cover Removers; and I do hereby declare the following to be a full, clear, and exact description of the invention, such as will enable others skilled in the art to which it appertains to make and use the same.

My invention provides a simple and highly efficient so-called fruit jar cover remover, which is especially designed and particularly adapted for quickly and easily removing the covers of fruit jars of the type generally known as Mason jars, and which covers are applied to the glass jars by coarse screw-threaded engagement. This device is also equally well-adapted for tightly screwing the covers on the jar.

Generally stated, the invention consists of the novel construction and combination of parts hereinafter described and defined in the claims.

In the accompanying drawings, wherein like characters indicate like parts throughout the several views,

Figure 1 is a plan view with some parts sectioned, showing the improved device;

Fig. 2 is a vertical section taken on the line 2—2 of Fig. 1, showing the device applied to the cover of a Mason jar;

Fig. 3 is an end elevation of the device; and

Fig. 4 is a perspective view showing, in detail, the movable clamping head of the device.

The character *a* indicates a Mason jar having the usual metal cover *b*, which latter has coarse-pressed threads that engage coarse-molded threads on the neck of the jar.

The body or main member of the cover remover is in the form of a cast yoke, comprising arms 5 that diverge toward and are connected to the ends of an approximately semi-circular segment 6, that is formed with internal teeth or sharp ridge 7. The converging ends of the yoke at the outer extremities are united by an integral arm terminal or head 8, that is bifurcated in the plane of the yoke so as to afford vertically spaced ears

through which a rivet or pivot pin 9 is passed.

The numeral 10 indicates a clamping head formed with a flat stem 11 at its outer end and with a clamping segment 12 at its inner end. The clamping head 10 fits loosely in the crotch afforded by inwardly diverging or outwardly converging arms 5 of the main yoke, and the flanged inner edge of the head 10 is formed on the arc of the circle of the segment 6 and like the latter, is provided with teeth or sharp edge ridges 13.

The stem 11 of the head 10 slides freely through the space between the upper and lower ears of the arm terminals 8, and the pivot pin 9 is passed through a slot 14 in said stem. Near the inner extremity of the slot 14, the head 10 is provided with a cam-engaging lug 15.

The numeral 16 indicates a cam lever which is placed adjacent to and on top of the stem 11, works between the same and the upper ear of the head 8 and is pivoted on the pivot pin 9. The short end of this lever 16 is formed on a curved line that is eccentric to the axis of the pivot and is arranged to engage directly with the lug 15 of the clamping head 10.

The projecting end of the stem 11 affords an extension to the arm formed of the outwardly converging portion of the main yoke. When the lever 16 is turned to the position shown in Fig. 1, the clamping head 10 will be free for outward movement into such position that the device can be readily applied to or removed from the jar cover.

When the lever 16 is moved into a position parallel to, or approximately parallel to the stem 11, the cam end of said lever, active on the lug 15, will force the clamping head inward and cause the teeth 7 and 13 to so tightly clamp against or bite upon the cover *b*, that the latter may be turned with great force either for the purpose of removal from or application to the jar. When the lever 16 is approximately parallel to the stem 11, the two may be held together by one hand and by the same hand used as a lever extension to the converging portion of the yoke, thus affording a lever of such length that a jar cover can be removed even when very tightly stuck to the jar, and moreover this can be accomplished

without damage to the cover and without danger of breaking the jar.

By reference particularly to Fig. 2, it will be noted that the teeth 7 and 13 are not on the arc of the cylinder, but follow a conical surface that has a downward flare. This gives the proper arrangement for full engagement of the teeth with the downwardly flaring cover *b* and increases the range of adjustment for application of covers of different size.

What I claim is:

1. A cover remover comprising a rigid yoke-like body, having an internally toothed segment and an extended crotch, a clamping head working in the crotch of said yoke with its stem projecting through the same and having at its inner edge a toothed segment, and a lever pivotally connected to the crotch of said yoke and operating on said clamping head to force the same inward.

2. A cover remover comprising a rigid yoke-like body, having an internally toothed segment and an extended crotch, a clamping head working in the crotch of said yoke with its stem projecting through the same and having at its inner edge a toothed segment, a lever working adjacent to the stem of said clamping head, pivotally connected to the crotch forming portion of said yoke and having a cam acting end operative on said head to force the same inward.

3. A cover remover comprising a yoke-like body, having an internally toothed segment and an extended crotch, a clamping head working in the crotch of said yoke with its stem projecting through the same and having at its inner edge a toothed segment, and a lever pivotally connected to the crotch of said yoke and operating on said clamping head to force the same inward,

the teeth on said yoke and clamping head being disposed around a downwardly tapering imaginary conical surface.

4. A cover remover comprising a yoke-like body, having an internally toothed segment and an extended crotch, a clamping head working in the crotch of said yoke with its stem projecting through the same and having at its inner edge a toothed segment, the crotch forming portion of said yoke having vertically spaced ears, a pivot pin extended through said ears, the stem of said clamping head having a slot through which the stem pivot pin is passed, said clamping head having a shoulder near the inner extremity of said slot, a clamping lever pivoted upon said pin, working between the ears of said yoke and having a cam acting end engageable with the shoulder of said clamping head to force the same inward.

5. A cover remover comprising a rigid yoke-like body formed with a segmental cover-engaging portion and an extended crotch, a clamping head working in the crotch of said yoke and having a stem projecting through the same and a lever pivotally connected to the crotch formation of said yoke and operating on said clamping head to force the same inward.

6. A jar cover device having in combination a rigid closed yoke member having an arcuate serrated portion at one end of its inner side, a concave segment disposed in its other end and having a stem projecting therefrom, a lever pivoted to said yoke member having one end bearing against said segment to move the same toward the serrated portion of said yoke.

In testimony whereof I affix my signature.
ANDREW B. MILLER.
